TIME RECORDER

Carl M. F. Friden, Piedmont, and John Renholts,
Oakland, Calif., assignors to Instograph, Ltd.,
Oakland, Calif., a corporation of California

Application June 9, 1931. Serial No. 543,078

16 Claims. (Cl. 185—40)

This invention relates to time recorders and the like and is particularly applicable to recorders which are electrically operated. In the co-pending application Serial Number 399,232, filed 5 October 12, 1929 by Carl M. F. Friden, a time recorder is disclosed in which the timing unit is adapted to be driven by a commercial source of regulated alternating current.

It is one object of the present invention to 10 provide a time recorder having timing means which is operable from a source of regulated or unregulated alternating current or from a source of direct current.

Another object is to provide a timing unit in 15 apparatus of the class described in which energy storing means is provided for driving the timing unit for a definite time interval and having means for automatically reconditioning the energy storing means at the termination of said time interval.

Another object is to provide a timing unit of 20 the character described which is instantaneously energized at regular intervals and which is unaffected in accuracy by fluctuations or failure of 25 the energizing current when such irregularities occur within the time interval between successive energizations.

Still another object is to provide a time recorder of the character described having a novel time 30 controlled switch for accurately controlling the energization of the timing unit.

Still another object is to provide a time recorder of the character described which is reliable and accurate in operation.

35 These and other objects and advantages are attained in the embodiment of my invention illustrated in the accompanying drawings, in which:

Fig. 1 is a side elevation of a time recorder 40 embodying the principles of this invention, the casing of the recorder being broken away to show the internal construction and certain parts of the device being shown in cross section.

Fig. 2 is a side elevation of the recorder shown 45 in Fig. 1 illustrating the internal construction thereof, as viewed from the opposite direction.

Fig. 3 is a detailed view of the timing unit 50 showing the novel time controlled switch of this invention mounted thereon.

Fig. 4 is a cross sectional view taken on the plane indicated by line 4—4 of Fig. 3.

Figs. 5, 6 and 7 are cross sectional views taken 55 on planes indicated by section lines 5—5, 6—6 and 7—7, respectively, of Fig. 4 showing certain constructional features of the timing unit.

Fig. 8 is a detailed view of a biasing spring employed in the time controlled switch of the recorder.

In its preferred form the time recorder of our 60 invention comprises time printing apparatus which is set by a suitable timing unit. The timing unit of the present invention preferably 65 comprises a clock mechanism which is driven for definite recurring time intervals by suitable energy storing means, such as a spring, the energy 70 storing means being automatically reconditioned at the end of each time interval by an electrical impulse to drive the clock mechanism for the next time interval, and so on, the clock mechanism 75 being operated indefinitely as long as electrical impulses are imparted at the end of each time interval to the means provided for reconditioning the energy storing means. Electromagnetic means is preferably employed for reconditioning the energy storing means and a time 80 controlled switch actuated by the timing unit controls the energization of the electromagnetic means. The time interval selected for reconditioning the energy storing means can be of any 85 desired duration and it is not essential from the view point of accuracy that this time interval be a standard unit of time. We have found that an interval of approximately one minute duration gives satisfactory results, but if desired, any suitable fractional part of a minute or multiple 90 of a minute can be chosen as the time interval.

The time between successive actuations of the 95 switch should be relatively consistent and it is also desirable that the time required for actuation of the switch be as constant as possible so that accurate compensation can be made in the timing unit for correcting any error which may be due to the switch actuation. In the embodiment of our invention illustrated in the accompanying drawings, both the period between successive actuations of the switch and the period required for each switch actuation are accurately controlled, thereby eliminating all errors attributable to these factors.

Referring now to the drawings, we have shown 100 a time recorder somewhat similar in general operation to that disclosed in the Friden application hereinabove referred to and the common features will be described herein only briefly, reference being had to the prior application for a more detailed description. As illustrated in the drawings, the operating parts of the recorder are enclosed in a suitable casing 16 which is provided with a slot 17 for the insertion of a sheet of paper 105 or the like on which the time is to be recorded. 110

One or more guiding arms 18 can be provided for directing the sheet into the path of a pair of contacts 19 and 21. Contact 19 is relatively movable and is adapted to be caused to engage the contact 21 by the force of the paper against the same.

Contacts 19 and 21 are adapted to control the energization of a solenoid 22 having a movable core 23 which strikes a plunger 24 when the solenoid is energized. The plunger 24 carries at its upper end a printing platen 26 and the force of the impact against the plunger 24 causes the platen to effect a printing stroke by lifting the inserted sheet and pressing the same against the printing surfaces of one or more type wheels disposed adjacent the upper portion of the slot 17. When the inserted sheet is raised in this manner it releases the contact 19 thereby permitting it to its normal position to deenergize the solenoid 22. One of the printing wheels is illustrated diagrammatically at 27 and a ratchet wheel 28 is adapted to be actuated step-by-step at regulated intervals to effect the setting of the printing wheels in a manner described in the aforementioned Friden application. An ink ribbon, not shown, is automatically fed by pawl mechanism indicated generally at 29 acting upon ratchet wheels 31 and 32 and controlled by a linkage of levers, of which 33 is one, set in motion each time the solenoid 22 is energized, as described in said Friden application.

The present application is more particularly concerned with a novel timing unit illustrated generally at 34 in Figs. 1 and 2 and shown in detail in Figs. 3 to 8, inclusive. The timing unit comprises a clock mechanism 36 driven for definite recurrent time intervals by energy storing means, such as a spring 37, reconditioned at the end of each time interval by electromagnetic means 38. The energization of the electromagnet 38 is controlled by a time controlled switch having a pair of contacts 39 and 41.

Contacts 39 and 41 are connected by leads 42 and 43 in a simple series circuit, or otherwise, with the electromagnet 38 and a source of operating current, which for the present purposes can be either direct current or regulated or unregulated alternating current, so that engagement of the contacts 39 and 41 causes energization of the electromagnet 38. Electromagnet 38 is provided with an armature 44, pivoted about a pivot 45, about which it is adapted to rock in a counter-clockwise direction, as viewed in Fig. 2, when the electromagnet 38 is energized. An extension 46 of the armature 44 is pivotally connected at its upper end to an arm 47 provided with a pawl 48 at its other end which engages the teeth on the ratchet wheel 28 of the printing mechanism. Thus, in the embodiment illustrated, ratchet wheel 28 is adapted to be moved step-by-step in accordance with the energization of the electromagnet 38 and thereby advance or set the printing wheels to impart the desired information. Suitable means, such as a spring 49, can be provided for biasing the pawl 48 into operative engagement with the teeth on the ratchet wheel 28.

Mounted on the pawl arm 47 is an extension 51 carrying a rod or pin 52 which passes slidably through an aperture in the one end of a lever 53 pivoted for rocking movement about the shaft 54 of a ratchet wheel 56. Movement of the pawl arm 47 to the left, as viewed in Fig. 2, effected by energization of the electromagnet 38, effects rocking movement of the lever 53 in a counter-

clockwise direction through the intermedium of the rod 52. If desired, yieldable means, such as a spring 55, can be interposed between the end 57 of the rod 52 and the lever 53 to make the force acting on lever 53 yieldable in nature. A 80 spring pressed pawl 58 is pivotally mounted on one end of the lever 53 and is adapted to engage the teeth of the ratchet wheel 56. The other end 59 of the lever 53 is connected to one end of the spring 37 which is employed to drive the clock mechanism of the timing unit. Upon rocking movement of the lever 53 in the manner heretofore described, the pawl 58 engages a succeeding tooth on the ratchet wheel 56 and the driving spring 37 is simultaneously tensioned. When the electromagnet 38 is deenergized the force of the spring 37 is directed through the lever 53 for imparting rotational movement of the ratchet wheel 56. Rigidly secured to the shaft 54 of the ratchet wheel 56 and mounted to rotate therewith is a gear 61 which constitutes one of the gears of the clockwork mechanism 36. An escapement mechanism, shown generally at 62 and illustrated in detail in Fig. 7, can be employed to regulate the rate of movement of the clockwork mechanism 100 36. The escapement mechanism 62 is not unlike the type commonly employed in watches and other time keeping devices. Since the ratchet wheel 56 is directly connected with the clockwork mechanism 36 the rate at which the ratchet 105 wheel is permitted to rotate and consequently the rate at which the energy in spring 37 is expended, is controlled by the clockwork mechanism 36. If the rate of movement is regulated in such a manner that the time required for 110 the ratchet wheel 56 to rotate a distance corresponding to one tooth is equivalent to a time interval of approximately one minute, then each time the lever 53 is actuated to engage a successive tooth sufficient energy will be stored in 115 the driving spring 37 to drive the clock mechanism for a corresponding time interval.

In the embodiment of our invention illustrated, the contacts 39 and 41 are parts of a time controlled switch which is adapted to be closed at 120 the termination of each of the selected time intervals to energize the electromagnet 38 and thereby effect the tensioning of the driving spring 37. Thus, we have shown the contacts 39 and 41 as being secured on arms 63 and 64 which 125 are mounted for pivotal movement about pivots 66 and 67, respectively. A pin 68 mounted on lever 53 passes through a slot 69 in arm 63 so that movement of the lever 53 in either direction effects a corresponding movement of the arm 63 130 about its pivot 66. Accordingly, when the lever 53 is moving relatively slowly in a clockwise direction under the force of spring 37 and at a rate which is determined by the clock mechanism 36 and ratchet wheel 56, the contact arm 63 follows 135 at a correspondingly slow rate and is moved toward the contact arm 64.

A biasing spring 71, preferably in the form of a loop, is fixed to the end of the arm 64 and has its looped end contacting against the upper 140 edge of the contact arm 63. The upper edge of arm 63 against which the biasing spring 71 bears is a cam surface and is shaped as shown, having a portion 72 extending approximately perpendicularly from one of the longitudinal edges of 145 the contact arm and a bevelled portion 73 which makes an obtuse angle with both the end portion 72 and the other longitudinal edge of the contact arm. The looped end of the biasing spring 71 is adapted to bear against the bevelled por- 150

tion 73 when the contacts 39 and 41 are in engagement and is adapted to bear against the perpendicular end portion 72 when the contacts are separated. The force of the spring 71 is directed downwardly against the end of the contact arm 63, as viewed in Fig. 3, and the force component acting between the contact arms 63 and 64 is such that when the spring bears against the perpendicular edge 72, the force of the spring tends to keep the contacts separated and when the spring bears against the bevelled portion 73, the force of the spring tends to keep the contacts in engagement. Thus, when the parts are in the position shown in Fig. 3 with the contacts 39 and 41 in engagement, the force of the spring 71 is directed downwardly and in a direction approximately parallel with the longitudinal center line of the contact arm 63. The bevelled end portion 73 against which the spring 20 bears acts as a cam surface under these conditions and as the end of the spring moves or tends to move along the portion 73, the contact 41 is caused to move into engagement with the contact 39.

When the contacts 39 and 41 are brought into engagement, the electromagnet 38 becomes energized and effects a rocking movement of the lever 53 in a counter-clockwise direction and the pin 68 moves therewith to the left, carrying with it the contact arm 63. The contact arms 63 and 64, being interconnected by the spring 71, both rock together about their respective pivots 66 and 67. During this movement the contacts 39 and 41 remain in engagement but there is a beneficial relative sliding movement between the contacts on account of the contact arms 63 and 64 being mounted on spaced pivots. This sliding action between the contacts 39 and 41 effects wiping of the surfaces thereof, thereby insuring a clean and firm contact. A stop member 74 projects into the path of the contact arm 64 and when the arm 64 strikes this stop, further movement of the contact arm 63 causes the spring 71 to slide along the bevelled end portion 73 toward the perpendicular end portion 72. Immediately upon the spring 71 passing the intersection between the portions 72 and 73, the force component of the spring acting between the arms 63 and 64 becomes such as to force the arms 55 violently away from each other, the arm 64 being forced against a back stop 76.

Energization of the electromagnet 38 in this manner tensions the spring 37 and when the electromagnet is deenergized upon opening of the switch, the force of the spring 37 tends immediately to restore the lever 53 and with it the lever 63 to the position shown in Fig. 3. Such movement, however, is delayed by the pawl 58 on the lever 53 which becomes engaged with a succeeding tooth on the ratchet wheel 56. The spring 37, therefore, must move the ratchet wheel 56 a distance corresponding to one tooth thereon before the switch contacts 39 and 41 will be restored to their engaging position. The rate at which the ratchet wheel 56 is permitted to rotate under the influence of spring 37 is accurately regulated by the clock mechanism 36 and the escapement mechanism 62, and assuming that this rate is such that the ratchet wheel 56 moves a distance of one tooth in a time interval of approximately one minute, for example, the contact 39 on arm 63 will be moved gradually to the contacting position in the same time interval. During this movement of the contact 39, the biasing spring 71 rests against the perpendicular

end 72 of the arm 63 and the force component acting between the arms 63 and 64 is such as to bias the same away from each other, the arm 64 being forcibly held against the stop 76. As the arm 63 moves toward the arm 64 the perpendicular end 72 of arm 63 slides against the looped end of spring 71 and just as the contact 39 is moved into contacting position, the bevelled end 73 of the arm 63 is moved adjacent the end of the spring 71. The point of application of the spring 71 thereby changes and immediately the force component acting between the contact arms 63 and 64 becomes such as to tend to draw the arms together. Arm 63 is constrained to move slowly, but the arm 64, being free to move about the pivot 67, is violently drawn toward the arm 63 thereby rapidly bringing the switch contacts 39 and 41 into engagement, as shown in Fig. 3. By this movement the contact arm 64 is caused to leave its position of rest against the stop 76, as illustrated. Upon closing of the switch the electromagnet 38 is energized to effect movement of the lever 53 so that the pawl 58 thereon engages the succeeding tooth of the ratchet wheel 56 and the driving spring 37 is retensioned simultaneously. Also, the pawl 48 moves the ratchet wheel 28 to effect the setting of the printing wheels of the recorder.

By providing biasing means such as that disclosed, the contacts 39 and 41 are held together until all of the parts have been reconditioned, thereby insuring that the electromagnet 38 will be kept energized until its armature 44 has been moved sufficiently to effect the desired operations. Since the biasing spring 71 effects a quick make and break of the switch contacts, the time required for each operation of the switch can be accurately determined and can be readily compensated for in adjusting the timing unit, thereby insuring a high degree of accuracy in the setting of the time mechanism.

Summarizing the operation of the recorder, the printing stroke is effected upon insertion of a sheet of paper or the like into the slot 17. The information recorded on the paper is determined by the setting of the printing wheels, of which 27 is one, and the setting of the printing wheels is controlled by the electromagnet 38, which upon each energization effects movement of the ratchet wheel 28 one step. The energization of the electromagnet 38 is controlled by the time controlled switch having the contacts 39 and 41 and this switch is adapted to be closed at the end of recurrent predetermined time intervals. The length of each time interval is determined by the timing unit which effects movement of the contact 39 toward the contact 41 at a relatively slow rate. During this movement of the contact 39, the force component of the biasing spring 71 is such as to force the contacts 39 and 41 away from each other, but upon reaching the position of contact, the force component of the spring acting between the contacts changes by reason of the change in the point of application of the spring on the arm 63, so that the contact 41 is violently drawn toward the slowly moving contact 39, thereby insuring rapid closing of the switch. The electromagnet 38 is thereupon energized and attracts its armature 44, thereby effecting actuation of the ratchet wheel 28 of the printing mechanism and simultaneously tensioning the driving spring 37 of the timing unit. The electrical impulse flowing through electromagnet 38 is of momentary duration since the circuit is broken as soon as its armature 44 has been moved a suf-

cient distance to effect separation of the contacts 39 and 41 through the arms 46 and 47 and the lever 53. Separation of the contacts 39 and 41 is effected by moving both contact carrying arms 63 and 64 toward the left, as viewed in Fig. 3, until the arm 64 strikes the stop 74. Continued movement of the arm 63, caused mainly by the momentum of the various interconnected parts causes the spring 71 to disengage the bevelled portion 73 of the arm 63 and to engage the perpendicular end portion 72 thereof. The force component acting between the arms 63 and 64 of the spring 71 then becomes such as to force the contacts 39 and 41 away from each other and contact 41 is quickly forced against its back stop 76.

The energy stored up in the driving spring 37 drives the clock mechanism 36 of the timing unit until the contacts 39 and 41 again make engagement and the cycle is then repeated. It will be noticed that the rate at which the clock mechanism is driven in the interval between electrical impulses is independent of the source of electrical energy and irregularities or even complete failure of the source during the period will have no adverse effect on the accuracy of the timing unit. So long as the impulse applied to the electromagnet is of sufficient magnitude to effect attraction of the armature 44, it is immaterial whether the source delivers regulated or unregulated alternating current or constant or pulsating direct current. The biasing arrangement afforded by the spring 71 insures quick make and break of the contacts 39 and 41 and the feature of biasing the contacts away from each other until the switch is about to be closed and biasing the contacts toward each other until the switch is about to be opened insures positive action of the switch at all times. All of these features of the time controlled switch contribute toward making the recorder accurate, inasmuch as the time consumed for actuation of the switch remains constant and accordingly accurate compensation can be provided therefor.

While we have shown and described a preferred embodiment of our invention, it is to be understood that we do not wish to be limited thereto, since the invention as defined in the appended claims can be embodied in a plurality of other forms.

We claim:

1. In a time recorder, a time controlled switch having a pair of movable contact members, resilient means effective only through said contact members for biasing said contact members away from each other, and time controlled means for shifting at least one of the points of application of said resilient means to effect biasing of said contact members toward each other.

2. In a time recorder, a time controlled switch having a pair of movable contact members, a single spring mounted on one of said movable members for biasing said contact members away from each other for a predetermined time interval and for urging said contact members together at the end of said time interval.

3. In a time recorder, a time controlled electric switch having a pair of movable contact members, resilient means entirely supported by said contact members for biasing said contact members away from each other for a predetermined time interval to maintain said switch open and for urging said contact members together at the end of said time interval to effect rapid closing of said switch.

4. In a time recorder, a time controlled elec-

tric switch having a pair of contact members, a single spring entirely supported by said contact members for biasing said contact members away from each other for a predetermined time interval to maintain said switch open and time controlled means operative at the end of said time interval to shift at least one of the points of application of said spring to effect biasing of said contact members toward each other.

5. In a time recorder, a base, an electric switch having a pair of contact arms movably mounted on said base, a single spring entirely supported by said contact arms for biasing said contacts away from each other for a predetermined time interval and means operative at the end of said time interval for causing said spring to urge said contacts together.

6. In a time recorder, a time controlled switch having a pair of movable contacts, means for moving one of said contacts toward the other at a definite rate and means for rapidly moving the other of said contacts to close the switch when the distance separating the contacts falls to a predetermined value.

7. In a time recorder, a time controlled switch, said switch having a pair of contacts each mounted on a pivoted arm, means for moving one of said arms toward the other at a definite rate and biasing means for moving the other arm to effect rapid closing of the contacts when the distance between the contacts reaches a predetermined value.

8. In a time recorder, a time controlled switch having a pair of movable contacts, means for moving one of said contacts relatively slowly and means for moving the other of said contacts relatively rapidly to effect closing of the switch.

9. In a time recorder, a time controlled switch having a pair of movable contacts, means for moving one of said contacts relatively slowly and means operative after a predetermined amount of movement of said slowly moving contact for moving the other contact relatively rapidly to effect closing of the switch.

10. In a time recorder, a time controlled switch having a pair of contacts, means for moving one of said contacts relatively slowly and a spring acting between said contacts for moving the other of said contacts relatively rapidly after a predetermined amount of movement of said slowly moving contact to effect closing of the switch.

11. In a time recorder, a time controlled switch having a pair of movable contacts, means for moving one of said contacts relatively slowly and means for moving the other of said contacts relatively rapidly after a predetermined amount of movement of said slowly moving contact to effect closing of the switch, means operative upon the closing of the switch to effect movement of both switch contacts in the same direction and at the same rate, and means operative after a predetermined amount of movement in said direction to effect separation of said contacts.

12. In a time recorder, a time controlled switch having a pair of contacts, means for moving one of said contacts relatively slowly and a spring for moving the other of said contacts relatively rapidly after a predetermined amount of movement of said slowly moving contact to effect closing of the switch, means operative upon the closing of the switch to effect movement of both switch contacts in the same direction and at the same rate, and means operative after a predetermined amount of movement in said direction

to effect separation of said contacts, said spring being adapted to aid said separating means to effect rapid separation of the contacts.

13. In a time recorder, a base, a pair of contact members articulated on said base, and a spring mounted on one of said contact members and abutting the other of said contact members for mutually biasing said contact members.

14. In a time recorder, a base, a contact member movably mounted on said base, and a spring bodily movable with respect to said base for biasing said contact member.

15. In a time recorder, a base, a first contact member movably mounted on said base and hav-

ing a cam surface, a second contact member movably mounted on said base, and a spring mounted on said second member and adapted to abut said cam surface.

16. In a time recorder, a base, a pair of contact members mounted on said base to pivot about different centers, and a spring mounted on one of said contact members and abutting the other of said contact members to bias said contact members together in one relative position thereof and to bias said contact members apart in another relative position thereof.
